UNITED STATES PATENT OFFICE.

WILLIAM M. KELLY, OF JERSEY CITY, NEW JERSEY, ASSIGNOR TO AMERICAN TYPE FOUNDERS COMPANY, OF JERSEY CITY, NEW JERSEY, A CORPORATION OF NEW JERSEY.

GRIPPER-ACTUATING MECHANISM.

1,339,654.

Specification of Letters Patent.

Patented May 11, 1920.

Application filed May 31, 1917, Serial No. 172,085. Renewed March 20, 1920. Serial No. 367,430.

To all whom it may concern:

Be it known that I, WILLIAM M. KELLY, a citizen of the United States, and resident of Jersey City, Hudson county, State of New Jersey, have invented certain new and useful Improvements in Gripper-Actuating Mechanism, of which the following is a specification.

This invention relates to printing presses and more particularly to means for actuating the grippers of the impression cylinder. In presses it is very important that the sheet be accurately positioned on, and firmly clamped to, the impression cylinder. One of the principal objects of this invention is to insure hair-line register by providing means which will compensate for any lost motion in the operating parts. To this end my invention consists in a provision of a supplemental means for actuating the gripping means during the final portion of its gripping movement, to which is momentarily transferred the function of operating the gripping means thereby relieving the main operating means so that any lost motion in the latter means is of no effect. Other features of the invention will be apparent from the description taken in connection with the drawings in which:—

Figure 1 is a side elevation of a portion of an impression cylinder, the cylinder housing and means for actuating the grippers; a portion of the cylinder being shown in section to illustrate certain parts in the interior thereof;

Fig. 2 is an end elevation of the parts shown in Fig. 1;

Figs. 3, 4 and 5 are diagrammatic views illustrating successive positions of the main and supplemental gripper actuating devices;

Fig. 6 is a top plan view of one end of the impression cylinder and the adjacent cylinder housing cap illustrating the arrangement of the supplemental gripper actuating means.

Referring to the drawings which illustrate the at present preferred embodiment of my invention the reference numeral 10 indicates the impression cylinder which is secured to the shaft 11 to rotate therewith. The shaft projects through one end of the cylinder and is supported in the cylinder bearing 12 which in turn is carried by the cylinder housing 13 and is secured in position by the cylinder housing cap 14. It will

be understood that the opposite end of the shaft 11 is properly supported in the frame of the press. The shaft 11 is formed with a bore 44 which extends from the right hand end thereof as shown at Fig. 1 for about three-fourths of the length of the same. A reciprocating rod 15 is mounted in this bore and the spring 16 is interposed between the end of the bore and the end of the rod, the opposite end projecting outside of the cylinder bearing 11 and carrying the two spaced collars 17 between which is located the sleeve 18 having the oppositely projecting blocks 19 which fit in forks 20 formed in the upper end of a lever 21 pivoted as at 22 on the cylinder housing and at its lower end rotatively carrying a roller 23 which is actuated by the gripper cam 24. The impression cylinder and gripper cam rotate in opposite directions as indicated by the arrows in Fig. 2 and the cylinder makes two revolutions for one revolution of the cam, the arrangement of parts being particularly adapted for a press having a two revolution impression cylinder.

The gripper rod 15 near its inner end carries a rack 25 which meshes with a spur gear 26 mounted on a stud 27 which is carried by the cylinder. Compounded with the gear 26 is a bevel pinion 27 which meshes with a miter bevel pinion 28 secured to the rock shaft 29. The rock or gripper shaft 29 is carried by the cylinder and has adjustably mounted thereon the gripper fingers 30. These fingers are formed with split eyes 31 at their inner ends which are adapted to be clamped around the rock shaft by means of cap screws 32 extending through the ears 33. Thus the gripper fingers may be angularly adjusted on the rock shaft 29. From the structure thus far described it will be apparent that rotation of the gripper cam 24 will act through the lever 21 to push the gripper rod 15 inwardly to thereby rotate the rock shaft 29 through the gearing and thus actuate the gripper fingers in a closing direction. The fingers are opened by means of the spring 16 which forces the gripper rod 15 outwardly. In order to properly control the motion of the gripper fingers in timed relation with the cycle of movements of the press the cam 24 is formed with a depressed portion 34 which extends between the inclines 35 and 36 and with a raised portion 37 which extends around the re-

maining part of the cam. When the roller 23 is on the high portion 37 the gripper rod 15 is in its inner position and the gripper fingers closed. When the roller 23 is on the 5 low portion 34 of the cam the rod 54 is in its outer position and the fingers are in raised or opened position. It is apparent that as there are several parts required to transmit the motion from cam 24 to the 10 fingers that there is opportunity for lost motion which interferes with the accurate operation of the fingers. In order to overcome or compensate for this lost motion I have provided a supplemental means which 15 acts directly on the gripper means and to which the operation of the fingers is momentarily transferred from the main cam 24 to complete the final portion of the closing motion of the fingers.

20 For this purpose the rock shaft 29 projects slightly from the end of the impression cylinder and has adjustably mounted thereon an arm or gripper closing finger 38. Arranged in the path of this arm and 25 adapted to coöperate therewith is a closing finger roll 39 rotatively carried by the roll bracket 40 which is secured on the top of the cylinder housing cap 14. The arrangement of this supplemental means and the 30 timing thereof with respect to the main gripper actuating means is clearly illustrated in Fig. 3, 4, 5 and 2. Referring to Fig. 3 it will be noted that the gripper cam roll 23 has just begun to ride up the inclined portion 36 of the gripper cam and that the cam arm 38 is very nearly in a 35 vertical position and has just come into contact with the closing finger roll 39, the fingers 30 being in the position illustrated.

40 As clearly shown in these figures the inclined portion 36 of the gripper cam is formed with a slightly depressed portion 40 and the inclined portion joins the high part 37. When the parts have reached the position shown in Fig. 4 the roller 39 has 45 become operative on the cam arm 38 to thereby rotate the rock shaft and fingers in a closing direction and has thus relieved the cam 24 from its function as the gripper cam roll 23 is opposite the slightly depressed portion 40 of the cam. The closing finger roll 39 continues to operate on the cam 38 to complete the closing motion of the gripping fingers whereupon the gripper cam roll 50 55 23 is engaged by the high portion 37 of the gripper cam and this latter cam takes up the further operation of the gripper fingers and continues to control the actuation of the same until the gripper cam has made substantially one complete revolution or until the gripper cam roll 23 again comes to the incline 36 and depressed portion 40. As the final closing movement of the grippers is made by means of the direct action of the 60 65 roll 39 on the arm 38 there can be no lost

motion and the fingers are therefore properly actuated. For further description of the details of construction of the impression cylinder and other parts of the press reference may be had to my copending application 820,042, filed February 20, 1914 and my Patent 1,092,998, granted April 14, 1914.

Although I have described my invention in connection with a two-revolution cylinder press and an impression cylinder having a particular means for actuating the fingers it is obvious that the invention is not limited to these details as they may be widely varied.

Having thus described the invention what is claimed and desired to be secured by Letters Patent is:

1. In a printing press having an impression cylinder, gripper fingers carried thereby, means for actuating the said fingers in timed relation with the cycle of movement of the press and coöperating means on the cylinder and press frame for taking over the operation of said fingers during the 90 final portion of their gripping movement.

2. In a printing press, an impression cylinder having a rock shaft and gripper fingers carried thereby, means for rocking said shaft in timed relation with the cycle of movements of the press, and coöperating means on the rock shaft and press frame for taking over the operation of said shaft during the final portion of its finger gripping movement.

3. In a printing press, an impression cylinder having a rock shaft and gripper fingers carried thereby, means for rocking said shaft in timed relation with the cycle of movements of the press, and an arm on the rock shaft and a coöperating roller on the press frame for relieving said first mentioned means and operating said shaft during the final portion of its finger gripping movement.

4. In a printing press, an impression cylinder having a rock shaft and gripper fingers carried thereby; means for rocking said shaft in timed relation with the cycle of movements of the press including a continuously moving member independent of the cylinder and connections between said member and shaft; and means to eliminate the effects of backlash in said connections during the final portion of the closing 120 movement of the fingers, including an arm on the rock shaft and a coöperating stationary roller for relieving said first means and operating the shaft during the final portion of its finger gripping movement.

5. In a printing press, an impression cylinder having a rock shaft and gripper fingers carried thereby; means for rocking said shaft in timed relation with the cycle of movements of the press including a con-

tinuously moving member independent of the cylinder and connections between said member and shaft; and means to eliminate the effects of backlash in said connections 5 during the final portion of the closing movement of the fingers, including a member rigid with said shaft and means directly operative on said member for relieving said first means and actuating the shaft during 10 the final portion of its finger gripping movement.

6. In a printing press, an impression cyl-

inder having a rock shaft and gripper fingers carried thereby, a continuously rotating cam and connections whereby the 15 cam rocks the shaft in timed relation to the cycle of movements of the press, and means independent of said cam and connections directly operative on the shaft to take over the operation of said shaft during the final 20 portion of the closing movement of the fingers.

In testimony whereof I affix my signature.

WILLIAM M. KELLY.
